Primary Examiner — Marissa J Cash(74) *Attorney, Agent, or Firm* — ScienBiziP, P.C.(57) **CLAIM**

The ornamental design for an aircraft with camera, as shown and described.

DESCRIPTION

FIG. 1 is a first, front perspective view of an aircraft with camera, in a state in which a camera is in a closed/protected position;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a second front perspective view thereof, in a state in which the camera is in an open position;

FIG. 10 is an enlarged view of the portion 10 of FIG. 1; and, FIG. 11 is an enlarged view of the portion 11 of FIG. 2.

The broken lines illustrate portions of the aircraft with camera that form no part of the claimed design.
